UNITED STATES PATENT OFFICE.

CLARENCE N. SCOTT, OF BUFFALO, NEW YORK, ASSIGNOR TO INTERNATIONAL STEAM PUMP COMPANY, OF NEW YORK, N. Y., A CORPORATION OF NEW JERSEY.

BLOWING-ENGINE AND THE LIKE.

1,150,069.

Specification of Letters Patent. Patented Aug. 17, 1915.

Application filed June 25, 1910. Serial No. 568,782.

To all whom it may concern:

Be it known that I, CLARENCE N. SCOTT, a subject of the King of England, residing at Buffalo, county of Erie, and State of New York, have invented certain new and useful Improvements in Blowing-Engines and the like, fully described and represented in the following specification and the accompanying drawings, forming a part of the same.

5 This invention relates to an improved blowing engine or pump of that type in which the piston moves on a hollow trunk extending through the cylinder, the especial object of the invention being to provide a 10 blowing engine of this type which shall be more compact, and simpler and stronger in construction than those heretofore designed.

15 The invention is intended especially for large blowing engines, but may be used in other similar air or gas pumps or compressors in which large capacity is required.

20 In accordance with my invention, the hollow trunk is used for admission, and the discharge is at the ends of the cylinder, the 25 admission of air from the trunk to the cylinder being controlled by mechanically operated valves, and the discharge preferably by automatic or pressure operated valves. The use of the longitudinally moving cylinder or 30 ring valves for controlling the admission ports and of an admission chamber outside the cylinder is thus avoided and important results in compactness, simplicity of construction, strength and reduced weight of 35 parts thus secured.

40 The invention includes, in addition to the above general features, certain detail combinations of parts, all as fully described hereafter and particularly pointed out in the claims.

45 In the accompanying drawings forming a part of this specification, there is shown a blowing engine of the preferred form embodying the invention, in which drawings:—

50 Figure 1 is a side elevation of the blowing cylinder and part of the driving mechanism. Fig. 2 is a cross section on the line 2 of Figs. 1 and 3. Fig. 3 is a longitudinal central section of the blowing cylinder.

55 Referring to said drawings, A, B are the inboard and outboard heads of the engine, C the cylinder body connecting the heads, D the piston, E the central trunk, F the air admission pipe connecting with the outer end 55 of the trunk, and G the discharge pipes

from the discharge chambers in heads A, B, shown as combining outside the engine into the single blast pipe. It will be understood, however, that any suitable delivery connecting with the discharge chambers may be 60 used.

The trunk E has the two series of annular admission ports 10 opening to the cylinder, and these ports are controlled by valves 11 carried by valve rod 12, these valves being 65 hollow to permit the air to pass through them to the inboard end of the trunk. The cylinder is provided at its ends with discharge openings controlled by automatic or pressure operated valves 13, which may be 70 of any common or suitable form, and through which the air is delivered from the cylinder to discharge chambers 14. The discharge openings and valves are preferably 75 in the heads A, B, as shown but may be in the cylinder wall at the ends of the cylinder.

80 The cylinder C is preferably made in two longitudinal sections 15, 16, as usual in such large engines, but an important feature of the cylinder shown, by which convenient access to the piston and piston rings is secured without disturbing any parts of the engine except half the cylinder, consists in the division of the outboard end 16 of the cylinder into sections circumferentially of the cylinder, 85 this end of the cylinder being shown as formed in halves secured together by flanges and bolts 1, and the engine is preferably supported independently of this end of the cylinder, so that free access to the piston 90 and piston rings is afforded by simply unbolting these two halves of section 16 and removing them.

95 The piston D and valves 11 may be operated by any suitable means. As shown, the piston D is driven by rods 17 at opposite sides of the piston passing through the inboard head and connected to cross head 18 on the main piston rod of the motor engine. The valve rod 12 carries cross head 100 19 connected by lever 20 and link 21 to crank 22 on the main crank pin driven by crank rod 23 from the cross head 18.

105 It will be seen that the construction is very compact as compared with previous blowing engines, this compactness of structure reducing largely the size and weight of parts. Great strength is secured, also, as the heads are connected and tied together by the stationary cylinder of approximately 110

the full diameter of the heads. The trunk need not be relied upon for tying the heads together, as this result is efficiently secured by the stationary cylinder, so that the trunk 5 may be lighter than when relied on to connect the heads. The large trunk required for free admission of a large quantity of air reduces the depth of the piston and affords a large bearing surface for it so that 10 a simpler form of piston may be used on account of its large bearing surface and reduced weight. The mechanism for reciprocating the admission valves is simpler, lighter and more compact than with the 15 movable cylinder or ring valves.

It will be understood that the invention is not limited to the exact form or arrangement of the parts shown, but that modifications may be made therein without departing 20 from the invention as defined by the claims.

What I claim is:

1. A blowing engine or pump having a stationary cylinder and a stationary hollow trunk extending through the piston and having cylinder inlet ports through the trunk, mechanically actuated inlet valves controlling said inlet ports, and discharge ports and valves at the ends of the cylinder. 25
2. A blowing engine or pump having a stationary cylinder and a stationary hollow trunk extending through the piston and 30

having cylinder inlet ports through the trunk, mechanically actuated inlet valves controlling said ports, and discharge ports 35 and valves in the cylinder heads.

3. A blowing engine or pump having a stationary cylinder and a stationary hollow trunk extending through the piston and having cylinder inlet ports through the 40 trunk, mechanically actuated inlet valves controlling said inlet ports, and pressure operated discharge valves at the ends of the cylinder.

4. In a blowing engine or pump, the combination with cylinder heads forming discharge chambers, a stationary cylinder connecting said heads, and the piston, of a hollow trunk extending through the cylinder and piston and open for admission at one 45 end, having cylinder inlet ports through the trunk, mechanically actuated inlet valves moving in the trunk and permitting the passage of air through them from the inlet end of the trunk, and discharge ports and valves 50 at the ends of the cylinder.

In testimony whereof, I have hereunto set my hand, in the presence of two subscribing witnesses.

CLARENCE N. SCOTT.

Witnesses:

R. WINTZER,
T. T. BRYEN.
